ARCOGRAPH

Frank N. Johnson, Cincinnati, Ohio

Application June 1, 1933, Serial No. 673,869

4 Claims. (Cl. 33—27)

My invention relates to an arcograph or an instrument for describing arcs of circles without reference to a center point. The instrument of the instant application belongs to that class of arcographs which employs two intersecting straight lines which are fixed by the fiducial edges of two straight edges, the lines being kept constantly in contact with two fixed points on a circular curve in order to make the point of intersection describe the curve when the latter point is moved from one of the fixed points towards the other. These devices are most advantageously used in scribing circles having extremely long radii.

One of the objects of my invention is to provide an arcograph of simplified construction which can be used with extreme facility. This is accomplished partly by employing two straight edges rotatable with respect to each other about a fixed point and so constructed and assembled as to eliminate all interferences to the vision or to the operation of a scribe tool. It is a further object of the invention to maintain the axis of rotation in the lines of the fiducial edges of the straight edges and to point out the location of this axis. A further object is to provide novel means for readily maintaining a manually manipulated scribe tool in proper position.

In order to accomplish these and other objects of the invention my arcograph is comprised of a pair of straight edges rotatable with respect to each other about an axis with means for maintaining the edges in predetermined relative positions and in forming one fiducial edge continuous through the intersection of the lines of the fiducial edges.

In the particular embodiment of my invention selected for illustration:

Fig. 1 is a top plan view of my device,

Fig. 2 is a bottom plan view of same,

Fig. 3 is an elevation of the device, part of the straight edges being broken away,

Fig. 4 is a diagrammatic view illustrating the operation of my device,

Fig. 5 is an enlarged section on the line 5—5 of Fig. 1, and

Fig. 6 is an end view partly in section and partly broken away.

Referring now to the drawing:

The device is comprised of coacting straight edges 10 and 11 having working or fiducial edges 12 and 13 respectively. Near its inner end the straight edge 11 is preferably provided with a plate 14 secured to the straight edge in any desirable manner such as by means of brazing. The plate 14 is provided with upwardly extending lugs

15 and 16 and carries a screw threaded aperture 17 for the purpose hereinafter described.

Near its inner end the straight edge 10 is provided with a plate 18 and intermediate plate 19 secured to the straight edge by screws 20 or in any other suitable manner. The plate 18 is preferably provided with an arcuate slot 21 in which the lugs 15 and 16 of the plate 14 are guided so as to permit rotation of the straight edges 10 and 11 about a fixed axis with respect to each other. A clamp screw 22 has its threaded end pass through the slot 21 and is received in the threaded aperture 17 so that its shoulder 24 seats against the plate 18 maintaining the straight edges in a predetermined relative position.

The straight edges 10 and 11 are both at their inner ends preferably beveled rearwardly and outwardly, the straight edge 11 being provided with a nose 25 which slides under the lip 26 on the straight edge 10. Raising of the straight edge 11 above the level of the under face of the straight edge 10 permits movement of the instrument over the paper in scribing a curve so that no part of the curved line made is contacted by the instrument, so that the ink slot of a ruling pen if used as a scribing tool is free of contact with the fiducial edge so as not to smudge the paper.

The instrument is preferably provided with a scribe tool guide 27 whose end preferably extends beyond the fiducial edge 12. The member 27 is secured for rotation on the top of the plate 18 by means of a clamp screw 28 which passes through the guide 27 and is screw threaded into the plate 18. The upper face of the straight edge 10 is preferably provided with an index mark 29 at the axis of rotation of the two edges and the guide 27 is set in the desired position to maintain the scribe tool point at the index mark in scribing an arc. (The scribe tool guide 27 is preferably made adjustable since with different shapes and sizes of pens and pencils used in scribing the arcs, the points will not always touch the paper when held against the guide, if it is fixed or always remains in the same position. It is obvious that if a thin stylus and a broad ruling pen were both held at the same angle against the scribe tool guide, their points would touch the drawing paper at different places and consequently the guide must be moved to a position necessary to cause the pen point to touch the paper near the index mark 29.)

To facilitate the drawing of arcs I have provided novel tacks 30 each of which is provided with a flange 31 and points 32 and 33 extending in opposite directions at right angles to the flange

so as to permit the end of the plate 18 to pass over them in scribing an arc. Of course, one end of the tack holds the work sheet to the drawing board and the other end acts as a guide for a fiducial edge of the instrument.

When employing the preferred form of my device, and assuming that a curve X is to be drawn, suitable points in the curve are platted in any preferred manner. If three points in the curve, 10 as A, H and G are platted, as at the ends of chords AH, GH and AG, the curve may be readily produced by inserting one of the tacks 30 in the drawing board at each of the points A and G, and adjusting the straight edges into such angular 15 relation that the working edges of the respective straight edges rest against the upwardly extending pins of said tacks at A and G, and the index 20 29 at the fiducial edge of the straight edge 10 is coincident with the point H. The parts are clamped in this relation, by tightening the clamp screw 22. This places the fiducial edges of the straight edges in coincidence with the chords AH and GH of the curve to be produced.

The guide 21 is thereupon adjusted, so that the 25 point of the scribing instrument immediately above its extreme lower end rests against the working edge of the straight edge 10 at the index 29, which is raised slightly above the paper or material, with a part of the scribing instrument 30 adjacent to and above said point resting against the contact edge of the guide 21, the scribing tool being manually slanted in selective position for most convenient manipulation by the operator, and for proper relation of the scribing point with 35 the paper or material so as to produce a continuous curve by movement of the working edges of the straight edges along the pins at the points AG, which will cause the scribing of a curve along the curve X throughout the range of contact of 40 the respective straight edges with the pins at the points AG, and permit the passage of the plate 18 over the pin at the point G, whereby the full measure of the curved line may be produced.

After the curved line from A to G is scribed, 45 other points along the curve may be found and the pins accordingly set, and the angular relations between the straight edges adjusted for coincidence of the index with the intermediate point found, as hereinbefore described. If the new 50 points found are equidistant with the previous points used along the curve, further adjustment of the instrument is unnecessary.

The operator may choose any method of plating such points. Given any three points on a 55 curve that the working edges will reach, a portion of the arc between them can be scribed, and from other points other portions of the curve can be located, and thus the curve be completed between the desired limits.

The device itself is useful for locating such 60 points. Points outside or inside the limits of the arc which has been assumed to be of convenient length may be located by the use of auxiliary straight edges held in contact with the fiducial edges. If the device be adjusted to describe the

arc AG then the index will always indicate a point on this curve, whether it be outside or inside the arc AG, provided that the line of one fiducial edge passes through A and the other through G. If the distance AG be inconveniently 5 long, supplementary intermediate points may thus be located. Moreover, if the device be adjusted to describe the arc AG, then if the index be at one extremity of this arc and one fiducial edge at the other extremity, the other fiducial edge 10 will be tangent to the arc. Then, if the device be rotated about the index until the first mentioned fiducial edge be brought into the line of this tangent, then the other fiducial edge will cross the arc produced, at a point distant from 15 the index by the length AG.

Concentric curves may readily be drawn with 20 this instrument without resetting the device by offsetting the pins by equal intervals along their respective radial lines.

While the invention has been described above in its preferred form, it will be obvious that various changes and modifications can be made therein without departing from the spirit or scope thereof and it is therefore desired that only such 25 limitations be imposed thereon as are necessitated by the prior art or specifically set forth in the claims.

I claim:

1. An arcograph having in combination a pair 30 of straight edges, lugs on one of said straight edges near one of its ends, a slot on the other of said straight edges coacting with said lugs to guide the relative angular movement of said straight edges and means for maintaining said straight edges in a predetermined angular relationship.

2. An arcograph having in combination a pair 40 of straight edges, means for rotating said straight edges with respect to each other about a fixed axis, an index on one of said straight edges on the axis and an adjustable scribe tool guide extending beyond said straight edges adjacent the index.

3. In an arcograph, the combination of a pair 45 of straight edges provided with working edges, a plate provided with an arcuate guide at the inner end of one of said straight edges, a coacting guide at the inner end of the other of said straight edges, clamping means for clamping said straight edges in adjusted angular positions, one of said straight edges provided with an index coincident with the center of the arcs of said arcuate guides, said center being in the line of said working edges, and a scribe tool guide adjacent to said index, and arranged for manually guiding a scribe tool 50 maintained at said index.

4. An arcograph having in combination a pair 60 of straight edges, a plate secured to one of said straight edges and having an arcuate slot therein, lugs on the other of said straight edges coacting with the slot for rotating said straight edges in relation to each other about a fixed axis and clamping means for maintaining said straight edges in a predetermined angular relationship.

FRANK N. JOHNSON. 65
